UNITED STATES PATENT OFFICE.

HENRY W. YOUNGQUIST, OF MANCHESTER, NEW HAMPSHIRE, ASSIGNOR TO DRAPER CORPORATION, OF HOPEDALE, MASSACHUSETTS, A CORPORATION OF MAINE.

ROCKER-SHAFT SUPPORT FOR LOOMS.

1,393,416.

Specification of Letters Patent. Patented Oct. 11, 1921.

Application filed June 17, 1921. Serial No. 478,232.

To all whom it may concern:

Be it known that I, HENRY W. YOUNGQUIST, a citizen of the United States, and resident of Manchester, county of Hillsborough, State of New Hampshire, have invented an Improvement in Rocker-Shaft Supports for Looms, of which the following description, in connection with the accompanying drawing, is a specification, like 10 characters on the drawing representing like parts.

This invention relates to improvements in lay rocker shaft supporting means for looms and the object thereof is to provide means 15 for sustaining a part or all of the weight, which otherwise would be imposed through the rocker shaft upon its bearings.

It is found in practice that the constant rocking of the oscillating lay rocker shaft 20 produces a wearing of the shaft on its bearings which in time permits a play or lost motion in the bearings which interferes with the proper operation of the loom. An excessive wearing of the bearings lowers the lay to 25 such an extent that the feeler is likely to strike the wall of the shuttle instead of entering through the feeler slot therein. Furthermore, the looseness of the bearings permits a jumping of the lay and in some instances 30 an endwise movement of the lay, so that the movement of the lay is irregular. This interferes with the proper operation of the loom and, consequently, results in imperfect weaving.

35 I am aware that heretofore various means have been provided for supporting or adjusting the rocker shaft to compensate for the wear which occurs between the shaft and its bearings, such as are described in the patent to Davis No. 1,278,443, granted September 10, 1918, but in all such cases the supporting means act directly upon the rocker shaft itself. The object of the present invention is to provide 45 supporting means which act upon the instrumentalities carried by the rocker shaft and serve to sustain a part or all of the weight which otherwise would be imposed upon the bearings of the rocker shaft.

50 A further object of the invention is to provide a resilient supporting instrumentality of the character described, means preferably being provided for adjusting the tension upon such resilient means.

A further object of the invention is to 55 provide supporting means so constructed and located as to prevent endwise movement of the lay and thereby to cause the lay to move with certainty in a fixed path.

A further object of the invention is to provide 60 a supporting means of the character described which can be applied to any usual type of loom.

Other objects and features of the invention will more fully appear from the following 65 description and the annexed drawings and will be pointed out in the accompanying claims.

The invention is illustrated herein as applied to a loom of the well known "Northrop" 70 type, only such portions of the frame of the loom and the mechanisms supported by the rocker shaft being shown as are necessary to illustrate the application of the present invention thereto.

In the drawings:

Figure 1 is a transverse sectional view through the breast beam and lay of the loom illustrating the lay rocker shaft carrying the swords of the lay and the means for sustaining 80 the weight of the instrumentalities supported by said rocker shaft embodying my invention;

Fig. 2 is a detail front elevation of portions of the rocker shaft and one of the 85 swords and illustrating the supporting means mounted upon the lower web of one of the side frames which is shown in section; and,

Fig. 3 is a front view showing the position 90 of the supporting means applied to both ends of the loom.

The loom illustrated in the accompanying drawings comprises the usual side frames 1 of skeletonized form having a 95 lower web 2 and an upper web 3 and a horizontal support 4 for the usual breast beam. The lay rocker shaft 5 is mounted in suitable sleeve-like bearings 6 having lateral extensions 7 which are bolted to the webs 2 of 100 the loom side.

The swords 8 are provided at their lower ends with sleeves 9 which are mounted upon the rocker shaft 5 and secured thereto by set screws or bolts 10. The swords 8, the 105 lay 11, the reed 12, and the members which support the same constitute an oscillating frame which is carried by the rocker shaft

5 and is oscillated by the pitman 13 in the usual manner.

The construction thus described may be and is of the usual type. In such constructions the weight of the swords, the lay and other mechanisms which are supported by the swords is sustained by the rocker shaft 5 and the constant oscillation of the lay in time wears the rocker shaft or its bearing 10 or both, so that considerable lost motion is caused and eventually the lay is sufficiently lowered to interfere with the proper operation of the shuttle.

The present invention consists in providing means, preferably resilient means carried by the side frames, for partially or wholly supporting the weight of the swords, lay and other instrumentalities which otherwise would be carried upon the rocker shaft, 20 for the purpose of relieving the pressure of the rocker shaft on its bearings and, consequently, eliminating or reducing the wear between the rocker shaft on its bearings, so that improper operation of the lay, due to 25 wearing of the bearings, will be avoided.

A preferred form of supporting means which is illustrated herein comprises a bracket having a web 14 which is bolted preferably to the inner side of the web 2 of 30 the side frame and is provided with an upwardly extending forked portion, one arm 15 of which rests upon the upper edge of the web 2 of the side frame, while the other arm 16 desirably is reinforced by a strengthening web 17. The arms 15 and 16 are provided with alined journals in which a shaft 18 is mounted and preferably is secured by a set screw 19. A standard 20, preferably having a transversely extending cylindrical end 40 portion 21, is pivotally mounted upon the shaft 18. The upper end of the standard 20 extends through and is reciprocably mounted in a lug 22 extending laterally upon a bracket 23 which is secured by bolts 24 to 45 the lay sword.

Resilient means preferably are interposed between the bracket which is secured to the side frame and the bracket which is connected to the sword. As illustrated herein the 50 resilient means comprises a helical spring 25 which surrounds the standard 20 and at its lower end rests upon a washer 26 which seats upon and is adjusted by a nut 27, threaded upon the standard 20. The helical spring 25 is thus supported at its lower end upon the washer 26 and at its upper end supports the lay sword and the instrumentalities carried by the same. By suitable adjustment of the nut 27 a part or all of the 55 weight of the swords and the mechanisms carried thereby may be sustained upon the springs 25 at the ends of the loom. The pivotal mounting of the standard 20 enables the spring to act properly through the relatively 60 narrow arc of vibration of the lay swords so

that substantially all the pressure may be relieved from the bearings of the lay rocker shaft.

Inasmuch as the swords are located within the side frames and adjacent to them the 70 action of the supporting members for the swords serves to prevent any endwise movement of the lay which might result from loose bearings or other conditions. The construction of the supporting device is such 75 that it may be readily applied to any of the usual types of looms without modification of the structure of the looms.

It will be understood that the particular embodiment of the invention disclosed herein is of an illustrative character and is not restrictive and that various changes in design, construction, location or arrangement of parts may be made within the spirit and scope of the following claims. 80

Having thus described my invention, what I claim as new, and desire to secure by Letters Patent, is:

1. In a loom comprising side frames, a lay rocker shaft, bearings on said side frames 90 for said rocker shaft and a rocking frame including a lay carried by said rocker shaft and supporting means acting upon the rocking frame to relieve the pressure of said rocker shaft on its bearings. 95

2. In a loom comprising side frames, a lay rocker shaft, bearings on said side frames for said rocker shaft and a rocking frame including a lay carried by said rocker shaft and resilient supporting means acting upon 100 the rocking frame to relieve the pressure of said rocker shaft on its bearings.

3. In a loom comprising side frames, a lay rocker shaft, bearings on said side frames for said rocker shaft and a rocking frame 105 including a lay carried by said rocker shaft, supporting means mounted on said side frames acting upon the rocking frame to relieve the pressure of said rocker shaft on its bearings and means for adjusting said 110 supporting means.

4. In a loom comprising side frames, a lay rocker shaft, bearings on said side frames for said rocker shaft, lay-carrying swords mounted on said rocker shaft, supporting means carried by said side frames acting upon said swords to relieve the pressure of the rocker shaft on its bearings. 115

5. In a loom comprising side frames, a lay rocker shaft, bearings on said side frames 120 for said rocker shaft, lay-carrying swords mounted on said rocker shaft, supporting means interposed between said side frames and said swords acting to relieve the pressure of the rocker shaft on its bearings and positioned to counteract endwise movement of the lay. 125

6. In a loom comprising side frames, a lay rocker shaft, bearings on said side frames for said rocker shaft, lay-carrying swords 130

5 mounted on said rocker shaft, located between and adjacent to said side frames, yieldable supporting means interposed between said side frames and said swords acting to relieve the pressure of the rocker shaft on its bearings and to counteract endwise movement of the lay.

10 7. In a loom comprising side frames, a lay rocker shaft, bearings on said side frames for said rocker shaft and lay-supporting swords carried by said rocker shaft, and resilient supporting instrumentalities pivotally mounted on said frame engaging and supporting said swords.

15 8. In a loom comprising side frames, a lay rocker shaft, bearings on said side frames for said rocker shaft, and lay-supporting swords carried by said rocker shaft, supporting instrumentalities pivotally mounted 20 on said side frames having upwardly extending standards, springs on said standards and means on said swords slidably engaging said standards and supported by said springs.

25 9. In a loom comprising side frames, a lay rocker shaft, bearings on said side frames for said rocker shaft and lay-supporting swords carried by said rocker shaft, shoul-30 dered brackets secured to said side frames having standards pivotally mounted thereon, brackets on said swords slidably engaging said standards and helical springs surrounding said standards engaging said sword brackets and acting to relieve the

35 pressure of the weight on said rocker shaft.

10. In a loom comprising side frames, a lay rocker shaft, bearings on said side frames for said rocker shaft and lay-supporting

swords carried by said rocker shaft, shoul-40 dered brackets secured to said side frames having standards pivotally mounted thereon, brackets on said swords slidably engaging said standards and helical springs surroundings said standards engaging said sword brackets and acting to relieve the 45 pressure of the weight on said rocker shaft and means for adjusting said springs.

11. A lay rocker shaft supporting instru-50 mentality for looms comprising a pair of brackets having relatively reciprocable mem- bers adapted to be attached respectively to the side frame and sword of the loom and resilient means interposed between said brackets.

12. A lay rocker shaft supporting instru-55 mentality for looms comprising a pair of brackets adapted to be attached respectively to the side frames and swords of the loom, a standard pivoted on one of said brackets and reciprocably mounted on the other and 60 resilient means carried by said standard en- gaging the other bracket.

13. A lay rocker shaft supporting instru-65 mentality for looms comprising a pair of brackets adapted to be attached respectively to the side frames and swords of the loom, a standard pivoted on one of said brackets and reciprocably mounted on the other, re-70 sili-ent means carried by said standard en- gaging the other bracket and means on said standard for adjusting the tension of said spring.

In testimony whereof, I have signed my name to this specification.

HENRY W. YOUNGQUIST.
